UNITED STATES PATENT OFFICE.

JOHN JACOB TANNER, OF TOPEKA, KANSAS.

ANTIRATTLING DEVICE FOR WINDOWS.

1,201,111.

Specification of Letters Patent.

Patented Oct. 10, 1916.

Application filed July 10, 1916. Serial No. 108,417.

To all whom it may concern:

Be it known that I, JOHN J. TANNER, a citizen of the United States, residing at Topeka, in the county of Shawnee and State 5 of Kansas, have invented certain useful Improvements in Antirattling Devices for Windows, of which the following is a specification, reference being had therein to the accompanying drawing.

10 This invention relates to improvements in antirattling devices for windows, one object of the invention being the provision of a device of this character adapted to be connected in such a position as to insure a neat 15 fit to the sash and at the same time maintain the sash in any desired elevation without the use of weights and pulleys.

A further object of this invention is the provision of a device of this character which 20 is quickly and easily installed and which is simple, durable and inexpensive in construction, and thoroughly efficient and practical in use.

In the accompanying drawings:—Figure 25 1 is a front elevation of the window frame including the sashes, a portion of the frame being broken away to show the present antirattling and holding device in place. Fig. 2 is a section taken on line 2—2 of Fig. 1. 30 Fig. 3 is an enlarged detail view of one of the attachments *per se*. Fig. 4 is a cross section on line 4—4 of Fig. 3.

Referring to the drawings, the numeral 5 designates the window frame, which is provided with three guide strips 6, 7, and 8, the guide ways formed thereby being open 35 at the bottom to permit of the introduction of the two sashes 9 therein. The lower end of the frame is provided with the removable sealing member 10.

Each sash is provided intermediate of its ends and at opposite sides thereof with the recesses 11, and in each recess is adapted to be secured by means of the screws 12, the 40 casing 13. This casing has mounted therein the frame 14 in which is journaled upon the pin 15 a roller 16, while attached by means of the integral cleat 20 formed from the bottom of said frame intermediate of the ends thereof, is a double terminal flat spring 17, which, when the parts are in the position as shown in Figs. 2 and 4, engage the bot-

tom of the carrying casing and tend to press the roller outwardly into engagement with one of the guides.

The side plates of the frame at the ends thereof are provided with elongated notches 18 which surround the securing screws and coöperate therewith to limit the outward movement of the frame and roller, and yet 55 at the same time prevent the frame and roller from slipping from the casing when either one of the sashes are removed from the window frame.

From the foregoing description, it is evident with a device of this character that the present attachment may be readily placed in position and that by the resilient support of the roller the same is frictionally held against the adjacent portion of the frame 60 so that the window sash will not stick or adhere but will be maintained in any desired adjustment without the use of weights. It is also apparent that with this form of device, the sashes may be readily moved when 65 desired.

What I claim as new is:—

1. The combination with a window frame having a guide and a sash having two oppositely disposed recesses in the sides thereof of open through one wall of the sash, of an antirattling and resilient supporting device for the sash, one mounted in each recess and resiliently engaging its respective guides of the frame, each of said devices including a 80 rectangular casing open at one end, fastening devices piercing the casing and attaching the same to the sash, a frame slidably mounted in said casing and provided with limiting notches for engaging the fastening 85 devices, a spring interposed between the casing and the adjacent side of the frame for projecting the frame outwardly, and a roller carried by the frame and connected exteriorly of the casing.

2. The combination with a window frame having a guide and a sash having two oppositely disposed recesses in the sides thereof of open through one wall of the sash, of an antirattling and resilient supporting device 90 for the sash, one mounted in each recess and resiliently engaging its respective guides of the frame, each of said devices including a rectangular casing open at one end, fasten-

ing devices piercing the casing and attaching the same to the sash, a frame slidably mounted in said casing and provided with limiting notches for engaging the fastening devices, two integral cleats formed from the body of the frame, a double terminal flat spring attached to the frame by the cleats

and having the terminals thereof in engagement with the bottom of the casing, and a roller carried by the frame and normally projected exteriorly of the casing.

In testimony whereof I affix my signature.

JOHN JACOB TANNER.
